DESIGN FOR AN ICE BOWL

Russel Wright, New York, N. Y., assignor to The
Chase Companies, Incorporated, Waterbury,
Conn., a corporation

Application August 17, 1934, Serial No. 52,978

Term of patent 3½ years

To all whom it may concern:

Be it known that I, RUSSEL WRIGHT, a citizen of the United States, residing at New York, in the county of New York and State of New York, have invented a new, original, and ornamental Design for an Ice Bowl, of which the following is a specification, reference being had to the accompanying drawing, forming part thereof. The essential feature of the design is the bowl with an arm at one side curved upwardly and inwardly and terminating in a hook.

Fig. 1 is a perspective view of an ice bowl showing my new design;

Fig. 2 is a side view of the same; and

Fig. 3 is a side view at an angle of 90° from that shown in Fig. 2.

I claim:

The ornamental design for an ice bowl substantially as shown and described.

RUSSEL WRIGHT.
